(57) **CLAIM**

The ornamental design for a luminaire, as shown and described.

DESCRIPTION

FIG. 1 is a top perspective view of a luminaire, showing our new design.

FIG. 2 is a left side elevation view of the luminaire of FIG. 1, the right side elevation view being a mirror image of the left side elevation view.

FIG. 3 is a front elevation view of the luminaire of FIG. 1.

FIG. 4 is a rear elevation view of the luminaire of FIG. 1.

FIG. 5 is a top plan view of the luminaire of FIG. 1.

FIG. 6 is a bottom plan view of the luminaire of FIG. 1.

FIG. 7 is a top perspective view of the luminaire of FIG. 1, with shorter side walls.

FIG. 8 is a left side elevation view of the luminaire of FIG. 1, with shorter side walls, the right side elevation view being a mirror image of the left side elevation view.

FIG. 9 is a top plan view of the luminaire of FIG. 1, with shorter side walls; and,

FIG. 10 is a bottom plan view of the luminaire of FIG. 1, with shorter side walls.

Portions or features of the luminaire not shown in the drawings form no part of the claimed design. The broken lines in the drawings form no part of the claimed design.

1 Claim, 9 Drawing Sheets
